AUTOMOBILE STEERING WHEEL

Maurice F. Baldwin, Birmingham, Mich., assignor
to Chrysler Corporation, Highland Park, Mich.,
a corporation of Delaware

Application June 12, 1952, Serial No. 20,169

Term of patent 7 years

(Cl. D14—30)

To all whom it may concern:

Be it known that I, Maurice F. Baldwin, a citizen of the United States, residing in the city of Birmingham, county of Oakland, and State of Michigan, have invented a new, original, and ornamental Design for an Automobile Steering Wheel, of which the following is a specification, reference being had to the accompanying drawing, forming part thereof, in which:

Fig. 1 is a top plan view of an automobile steering wheel, showing my new design;

Fig. 2 is a side elevational view thereof; and

Fig. 3 is a sectional view taken on the line 3—3 of Fig. 1.

I claim:

The ornamental design for an automobile steering wheel, substantially as shown.

MAURICE F. BALDWIN.
